(57) **CLAIM**

The ornamental design for a quick release attachment device for a support head of video and photographic apparatus, as shown and described.

DESCRIPTION

FIG. 1 is a top, front and right side perspective view of a quick release attachment device for a support head of video and photographic apparatus showing my present design;

FIG. 2 is a top, front and left side perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a bottom plan view thereof;

FIG. 9 is a bottom and right side perspective view of a quick release attachment device; and,

FIG. 10 is a bottom and left side perspective view of a quick release attachment device.
